UNITED STATES PATENT OFFICE

HERMAN R. KARSTENS, OF CHICAGO, ILLINOIS.

BRIDGE-GATE.

SPECIFICATION forming part of Letters Patent No. 389,086, dated September 4, 1888.

Application filed April 23, 1888. Serial No. 271,630. (No model.)

To all whom it may concern:

Be it known that I, HERMAN R. KARSTENS, a citizen of the United States, residing at Chicago, Illinois, have invented certain new and useful Improvements in Bridge-Gates, of which 5 the following is a specification.

The object of my invention is to make the traffic and foot-gates which close the approaches to swinging bridges so that they will automatically close as the bridges open, and automatically open as the bridges close; and my invention consists in the figures and details of construction hereinafter described and claimed.

15 In the drawings, Figure 1 represents an elevation of my improved gate looking from the river; Fig. 2, a diagram of some of the operative parts by which the opening or closing of the bridge causes the gates to open or close; 20 Fig. 3, an enlarged sectional view of a part of Fig. 1; Fig. 4, a view, partly in section, taken through the line x x of Fig. 3, looking in the direction of the arrows; Fig. 5, a side elevation of one of the foot-gates when closing the 25 foot-walk; Fig. 6, an enlarged plan of one of the operative parts by which the foot-gate is opened or closed; Fig. 7, a side view of a part of Fig. 6, cut off by the line y y , indicated by the arrow; Fig. 8, a plan view of a section of 30 Fig. 1 taken through the line z z ; Fig. 9, a view taken in the line v v of Fig. 8, looking in the direction of the arrow; Fig. 10, a plan view of the gate taken through the line w w of Fig. 1; Fig. 11, a vertical section of one of the side 35 posts of the traffic-gates; and Fig. 12, a vertical section of one of the traffic-gate posts and its piston, taken through the line u of Fig. 8, looking in the direction of the arrow.

In the drawings, A represents the abutment 40 of the bridge; B, the traffic-gate posts; C, the traffic-gate; D, the foot-gates; E, the end of the bridge shown as ready for traffic; F, a traveling pulley-carrying block; G, pivoted dogs on the under side of the bridge by which 45 the traveling block with its pulleys is moved in one direction or the other as the bridge is opened or closed; H, cables which operate the traffic-gates; I, cables which operate the foot-gates; J, a hollow piston in the traffic-gate 50 posts; K, a shaft extending through the gate from one side to the other, carrying a pinion on each end; L, guides on the inner sides of

the traffic-gate posts, in which the edges of the gates and the shaft K with its pinions move up and down; M, a sliding rod for operating 55 the cables opening and closing the foot-gate, and N a piece on which one end of such sliding rod is pivoted.

In making my improved traffic-gate for swinging bridges I make it of suitable material and preferably as light in its construction as consistent with the necessary strength, and of a length to extend from one side of the traffic-way to the other. To give it the necessary strength, I prefer to provide it with truss-rods, 65 as shown in Figs. 1 and 10. At each side of the traffic-way on the abutment to the bridge I erect two hollow posts, which I have termed the "traffic-gate posts." These posts are also provided on their inner sides—by which I 70 mean the sides which face the traffic-way—with guiding-pieces and designated in the drawings by the letter L. As shown in Fig. 8 of the drawings, these guides turn toward each other at right angles to their inner edges. They 75 are intended to be of a size and width apart to permit the edges of the traffic-gate, which are preferably provided with a T-shaped head, as shown in Fig. 8, to be inserted in them, and to move up and down therein with steadiness 80 though with facility. One edge of these guiding-flanges L is intended to be provided with a rack, as shown in Fig. 9, and a shaft, K, is intended to pass from one side of the gate to the other, as shown in Fig. 8. This shaft rests 85 in bearings in the gate-frame and carries a pinion at each end to engage with the teeth of the rack in the gate-guides. The engagement of the teeth of these pinions with the teeth of the racks in the gate-guides at each 90 side of the traffic-way insures a regular and uniform movement of both sides of the gate up and down and prevents any binding or friction in the movement of the gate. As to the precise arrangement of these gate-guides 95 and racks and pinions, I do not wish to confine myself too strictly to details, as it is obvious that various changes could be made and yet secure the same regular and uniform movement of the gate up and down in its guides. 100

To prevent the gate from descending too rapidly when released, as hereinafter described, I make the gate-posts hollow, and preferably with a round interior. I arrange pistons J with-

in the gate-posts which are adapted to move up and down contrary to the movement of the gate. These pistons should move with proper freedom from friction, and yet they should 5 sufficiently fit the interior of the gate-posts as to practically, or at least largely, prevent the air that may be in the gate-posts above or below them from escaping past them. I provide the pistons with holes—one at each end—and 10 arrange a valve to close the upper hole in the piston, openable upward from a pressure below. These pistons are connected by a rope or other proper connection from their top ends, which may be provided with a bail, as shown 15 in Figs. 11 and 12, to the gate, so that as the gate goes down they will be drawn up, and as the gate goes up they will be permitted to slide down. Owing to the arrangement of the valves in these pistons, so that they are only 20 openable upward from a pressure below, it is obvious that as the gate descends and the pistons are drawn upward they will tend to compress the air in the upper portions of the gate-posts, which is allowed to escape slowly through holes 25 near the top of the gate-posts, through which the ropes pass, and which will thus operate as a brake to prevent the too rapid descent of the gate; but as the gates rise and the pistons descend, the air rushing into the pistons from 30 below will open the valves and pass into the upper portion of the gate-posts. Thus these pistons will be permitted to descend rapidly and the gates to rise with corresponding rapidity.

35 In order to provide for the automatic raising and lowering of the traffic-gates as the bridge is swung open or closed, I arrange within the ends of the abutments of the bridge at each side of the river space for a track or 40 way, as shown particularly in Figs. 1, 3, and 4 of the drawings. This track or way consists of two rails—one at the bottom of the space and one at the top—the upper rail being immediately above the lower and the 45 two rails facing each other. I then make a traveling pulley-carrying block, which I have designated by the letter F, which is provided with wheels on its under and on its upper sides to engage, respectively, with the upper and the 50 lower tracks. These wheels may be attached to the block in any desired way, as their office merely is to steady the block and enable it to be moved with facility in one direction or the other. This traveling block is furnished with 55 pulleys, which I have designated by the letter P, and which are particularly shown in Figs. 3 and 4 of the drawings.

In the space made in the abutments of the bridge, in which the track and traveling block 60 above described are arranged, I also preferably provide means, as a staple, S, to enable the ends of the ropes or cables to be attached. These ropes may be attached directly to the traveling block when, as in the case of very 65 wide bridges, the block travels sufficiently to one side or the other to raise the gate when

the rope is thus attached. I attach one end of each of two cables to this staple or other means for effecting a fastening and carry the other ends of the cables through the traveling block 70 and in contact with the pulleys P, arranged and carried therein. These cables are then passed around two stationary pulleys, R, pivoted in bearings in the lower part of the space made in the abutment of the bridge, and are 75 then carried one to the one side and the other to the other side of the abutment. These ropes are then passed around stationary pulleys j at the sides of the abutment, and are then carried back away from the face of the abutment 80 of the bridge until they pass around pulleys O at or within the bottoms of the traffic gate posts. They are then carried up within the hollow posts and attached to the bottoms of the pistons J. As the traveling pulley-carrying 85 block is carried toward the one side or the other of the bridge-abutment from its central position, it is obvious that it will carry the cables with it, and thereby shorten the portion which extends up into the traffic-gate posts, 90 and thus draw the pistons located therein toward the bottom. As these pistons descend, the ropes extending from their upper ends to the gates will draw the gates upward, so that when the traveling block is at one side or the 95 other of the bridge-abutment the gates will always be raised, so that teams may pass under them as traffic may require; but it is obvious that as the weight of the gate is thus suspended the tendency of the traveling block will always 100 be to run back to the center of the abutments, and that it will always come to this position unless positively held to the one side or to the other. When, therefore, any positive force holding it to the one side or to the other of the 105 abutment is removed, the weight of the gate will cause it to descend and the traveling blocks to go to the center of the abutments.

To move the traveling block from its normal position in the center of the abutments to 110 the one side or to the other, so as to raise the gates, I provide the under side of the bridge with means for engaging the traveling block and forcing it to the one side or to the other. These means, as I have shown them in the 115 drawings, consist of pivoted dogs G, which are held from moving in one direction by the pin or post p, attached to the under side of the bridge, but are enabled to move in the other direction against the pressure of the spring s 120 until they have reached another pin or post, q, arranged on the under side of the bridge to arrest their further movement in that direction. The heads of these dogs extend out somewhat beyond the ends of the bridge, so 125 that they may pass into the space arranged in the abutments of the bridge and engage with the traveling blocks F, which are preferably provided with beveled edges to enable the heads of the dogs to become disengaged when 130 the bridge is entirely open for the passage of vessels. The traveling blocks could, how-

ever, extend out far enough, so that it would not be necessary for the heads of the dogs to extend into the spaces of the abutments of the bridge. Both of these pivoted dogs are held by posts or pins on their inner sides, and are only openable against the springs *s* outwardly, as clearly shown in Fig. 2. As the bridge is being closed after the passage of a vessel, the dog on the side of the bridge which first moves up to the abutment of the bridge comes into contact with the traveling block, which is moved to its position in the center of the abutment as the gate descends, and carries it along with it away from the center of the abutment. As this block is moved away from the center toward the one side or the other, it carries the cables with it, as above explained, and lifts the gate. When the bridge has reached its normal position and is closed so that traffic may be resumed, the traveling block will be held at one side of the abutment, as shown in Fig. 2. If now it should be desired to open the bridge for the passage of another vessel, the dog *G* would move easily past the traveling block as the bridge began to open, which will release the traveling block and enable it to run back to its position in the center and the traffic-gate at the same time to descend. As the other dog then engaged the traveling block, the dog would be pushed back, as the spring would permit it to yield, so that it would pass the traveling block without moving it away from its position in the center. In this way the traveling block would be automatically allowed to return to the center of the abutments and the traffic-gates to close as the bridge was opened for the passage of a vessel, and automatically forced away from the center of the abutments and the gates raised as the bridge swung into its normal position for the resumption of traffic; but it is also desirable that the foot-walks at the sides of the traffic-way should be also automatically closed as the bridge is opened. These foot-gates may be constructed in any way desirable, though I have shown them in the drawings as consisting of two slats or bars arranged with connecting-links, like parallel-rulers. The upper one of these rulers is pivoted near its inner end to the traffic-gate post next to which it is located. The end extends somewhat beyond the pivot in the post, as shown in Fig. 5, and is provided with a cable or rope, *I*, which passes over a pulley, *o*, and around another pulley, *o'*, and passes through the end of the sliding rod *M*, whence it passes to a fixed point, to which it is attached. This rod *M* passes through two fixed eyes, *m*, and is provided with a coiled spring, as shown in Fig. 6, which is compressed whenever the foot-gate is down. The other end of the rod *M* is pivotally attached to a piece, *N*, which may be either a flexible or a jointed piece, as desired. When released from pressure, the coiled spring on the rod *M* forces the rod back against the piece *N* and bends it, as shown by dotted lines on the left hand of Fig. 2. In thus forcing the rod back the cable *I* is released from pressure, as shown in Fig. 6, and the weight of the foot-gate causes it to drop down in place. As the bridge turns to the one side or to the other, however, it bears against the piece *N* and forces it back out of its crooked position against the pressure of the spring, and forces the cable back, as shown in Fig. 6, which of course shortens or draws in the outer end of the cable, and so draws the foot-gate up into its position. (Shown in Fig. 1.) Whenever the bridge is closed for traffic, the rod *N* is held up in its normal position, so that the foot-gate is kept elevated; but the moment the bridge swings open for the passage of a vessel the spring on the rod *M* forces the rod back against the piece *N*, so as to create a slack in the cable *I* and permit the gate to fall, as above explained. The piece *N* is provided with slots, as shown in Fig. 7, to permit it to be bent back, as shown in Fig. 2. In this way the foot-gate is also automatically opened and closed by the opening and closing of the bridge, which preferably has the corners somewhat cut away, as shown in Fig. 2, to permit the foot-gate to begin to close the instant the bridge begins to move.

What I regard as new, and desire to secure by Letters Patent, is—

1. In a bridge-gate, the combination of a swinging bridge provided at each end with two pivoted dogs laterally movable in opposite directions to each other only, an abutment containing a track or way in its face, a pulley-carrying block traveling on such track or way and movable by the dogs to the one side of the abutment or the other, and a vertically-sliding traffic-gate connected by ropes or cables to the pulley-carrying block, whereby the gate is raised as the pulley-carrying block is moved by the dogs from its central position, substantially as described.
2. In a bridge-gate, the combination of vertical hollow traffic-gate posts, hollow pistons arranged in such gate-posts and movable up and down therein and provided with air-valves openable in one direction only, a vertically-sliding traffic-gate arranged in slides on the faces of such posts, ropes or cables running from the gates to the upper ends of the pistons, ropes or cables running from the lower ends of the pistons around pulleys and through a traveling pulley-carrying block to a stationary point of connection, and a pulley-carrying block moving in either direction from a central position and shortening the cables as it moves, and thereby raising the gate, substantially as described.
3. In a bridge-gate, the combination of vertical hollow traffic-gate posts having guides or ways on their inner or opposed faces, a rack arranged in each of the guides, a vertically-sliding traffic-gate arranged in the guides and provided with a horizontal rod or shaft extending from one side of the gate to the other,

and carrying pinions at its ends engaging with the racks in the guides, whereby the sides of the gates are raised or lowered together and with a uniform movement, substantially as described.

4. In a bridge gate, the combination of a pivoted foot-gate, a rope or cable extending around pulleys from the pivoted end of the gate through the end of a sliding rod to a stationary point of connection, a sliding rod mov-

ing back and forth in ways, and means for holding the rod back against the weight of the gate and allowing the gate to fall by its own weight when such means are released, substantially as described.

HERMAN R. KARSTIENS.
